United States Patent

Des. 238,524

Patented Jan. 27, 1976

238,524

SHOE SOLE

Jonas Senter, Greenwich, Conn., assignor to CITC
Industries Inc., New York, N.Y.

Filed June 19, 1974, Ser. No. 480,882

Term of patent 14 years

Int. Cl. D2—04

U.S. Cl. D2—321

FIG. 1 is a bottom plan view of a shoe sole showing my new design;

FIG. 2 is an enlarged sectional view taken along line 2—2 in FIG. 1; and

FIG. 3 is an enlarged sectional view taken along line 3—3 in FIG. 1.

I claim:

The ornamental design for a shoe sole, as shown.
